Primary Examiner — Karen E Eldridge Powers(74) *Attorney, Agent, or Firm* — Banner & Witcoff, Ltd.(57) **CLAIM**

The ornamental design for a baseball glove, as shown and described.

DESCRIPTION

FIG. 1 is a rear perspective view of a baseball glove showing my new design;

FIG. 2 is a left side view thereof;

FIG. 3 is a right side view thereof;

FIG. 4 is a top view thereof;

FIG. 5 is a bottom view thereof;

FIG. 6 is a rear view thereof; and,

FIG. 7 is a front view thereof.

The broken lines immediately adjacent to the shaded area represent unclaimed boundaries of the design. The broken lines showing the remainder of the baseball glove are for environmental purposes only and form no part of the claimed design.
